UNITED STATES PATENT OFFICE.

LEON A. WOODRUFF, OF COMPTON, ILLINOIS, ASSIGNOR OF ONE-HALF TO MAUD L. ANDERSON, OF AURORA, ILLINOIS.

DOOR HINGE.

Application filed September 22, 1926. Serial No. 136,972.

My invention relates to hinges of the concealed type having an arm composed of laminated parts.

One object of my invention is to provide a hinge which is strong and yet inexpensive to manufacture, the construction being of such nature that rattling and loose motion are practically impossible when in use.

Another object is to provide a hinge having a comparatively small depth so that only a shallow cut into the stationary vertical pillar is required for its installation. Also by means of its linked construction a large throwout is permitted so that a considerable clearance is provided when the door is opened, and yet when the door is closed the links fold into a very compact arrangement.

A further object is to provide an improved method of securing the hinge to the door of an automobile after the hinge has been mounted in the stationary vertical pillar.

A further object of my invention is to provide an improved casing for a concealed automobile door hinge of such construction as to enable it to be mounted in a recess cut by means of a circular cutter, thereby avoiding an expensive mortise, as used in similar hinge constructions at the present time.

30 A practical embodiment of the preferred form of my invention is shown in the accompanying drawings wherein,

Fig. 1 is a fragmentary view of an automobile body and door indicating thereon the location of my concealed door hinges.

35 Fig. 2 is a sectional side elevation showing three hinges supporting an automobile door.

Fig. 3 is a horizontal sectional view taken 40 through a door and a stationary pillar showing a plan view of the hinge in its closed position at the beginning of the throwout.

Fig. 4 is another view thereof with the hinge in its fully opened position, showing 45 the extent of the throwout.

Fig. 5 is a perspective view of the hinge in open position.

Fig. 6 is a perspective view of the hinge casing illustrating the manner in which it 50 may be mounted in the milled groove shown in connection with it.

Fig. 7 is a side section of one form of my two part door bracket.

55 Fig. 8 is an elevation of another modification thereof, and

Fig. 9 is a further modification of a detail of the hinge.

Referring more particularly to the drawings the locations of the concealed hinges 10, 11 and 12 are shown in the automobile body 60 13, having a door 14. In Fig. 2 three hinges are shown mounted in a vertical line in the door groove, the hinge 12 being designed to take care of the curve in the body of the automobile. Fig. 3 shows the compact arrangement of the various links that make up the hinge mounted in the stationary vertical pillar 15, with the door 14 in closed position. It will be readily seen that this construction requires only a shallow cut into the pillar, 70 thereby preserving practically the full strength thereof. Fig. 4 shows the door 14 open fully at an angle of ninety degrees to the body and illustrating the large throw obtainable through my arrangement of the 75 links of my hinge, which is a very desirable feature in automobile design. As shown in

Fig. 5, the stationary base plate 16 has a central projection or horizontal bar 17 formed integral therewith to which one end of the 80 main links 18, 18' are pivoted at 19. The other end of the links, 18, 18' are pivoted at 20, 20' to the reduced end of the rocker or pivot block 21. Another pair of main links 22, 22' are pivoted at 23, 23' to the unreduced portion of the plate 16, so that in operation the links 22, 22' may slide smoothly and without binding over the links 18, 18' respectively. The other ends of the links 22, 22' have enlarged ends which are pivoted 85 at 25, 25' to the rocker block 21, and at 22^a, 22^b to the links 24, 24' respectively. The auxiliary links 24, 24' are also pivoted at 26, 26' to the lugs 27, 27' respectively. These lugs project horizontally from the movable 90 plate or butt member 28 and are formed integral therewith. The lugs 27, 27' are also pivoted at 29, 29' to the rocker block 21.

The main links 18, 18' and 22, 22' control the movement of the hinge in a pre-determined path and together with the auxiliary links 24, 24' and the rocker block 21 give the hinge the desired amount of throwout. The rocker block is formed of a solid piece of metal and forms a base to which the 100 links 18, 22, lug 27, and the links 18', 22' and lug 27' may be pivoted. This block forms a bearing surface also for the aforementioned links and lugs and gives great 105 strength to the hinge as a whole. The edges 110

and sides of the various links and lugs are curved so as to give clearance to each other throughout the various stages of the hinge movement and also so that they will occupy a minimum amount of space when the hinge is closed. The forward lateral edge of the rocker block 21 adjacent the plate 28 is curved sufficiently to give the plate clearance when in operation. The plate 28 is slotted at 30, 30' sufficiently to give clearance to the links 24, 24' respectively, said links extending through plate 28 and to the outer surface thereof. In this manner additional compactness of the hinge is secured.

15 The base plate 16 is rounded at its rear corners as shown in Fig. 5, for instance, whereby it can be firmly anchored by screws in the curved opening 31 of the pillar 15, thus obviating the labor of cutting the rectangular mortises as required by the general practice at the present time. In Fig. 6 I have shown a shell 32 which is designed to enclose all but the face of the base plate 16 to protect the same against moisture, etc.

20 25 The shell 32 is shaped to fit within the opening 31 and is provided with holes 33 through which the screws pass from the plate 16 into the pillar 15.

As illustrated in Fig. 5, the hinge proper 30 is preferably secured to the door 14 by means of a plate 34 first attached to the door by screws 35. The plate 34 terminates at its upper end in a flange 36 which forms a channel for the upper edge of the butt member 28 of the hinge. Screws pass through the openings 37 in the butt member and openings 38 in the plate for retaining the hinge in position. By removing the last mentioned screws, the door can be removed 35 40 very conveniently as will be understood. In replacing the doors, the flange 36 guides the butt member whereby the holes 37 are brought into registering relation with the holes 38 of the plate.

45 In Fig. 8 a modified form of the plate is shown and is indicated by numeral 39. Plate 39 differs from plate 34 in that it has a pair of flanges 40 and 41 which embrace the ends of the butt member 28. The flanges are 50 preferably arranged to provide converging channels arranged to limit the movement of the butt member 28 at the position where the holes 42 register with the holes 43 of the butt and plate respectively. The flanges 55 provide a very secure means of attaching the butt to the plate, the screws which pass through the holes 42 and 43 serving to prevent lateral movement of the butt, as will be seen. The modification shown in Fig. 8 60 may also comprise a stop member or lug 44 on the plate 28 which seats in the recess 45 in the butt member when the two members are in operative position. The lug 44 serves to center the butt member with reference to 65 the plate to cause the screw holes to register

properly and it also acts as a stop, as will be seen.

In Fig. 9, the plate 46 is adapted to be attached to a door of an automobile similarly to plates 34 and 39, previously described. The plate 46 has an overturned upper flange 47 which is cut away at each upper corner, whereby the said flange can be lowered into the recess 48 formed in the upper edge of the butt plate 49 which corresponds to the previously described butt 70 75 80 85 90 95 100 105 110 115 120 125 130 135 140 145 150 155 160 165 170 175 180 185 190 195 200 205 210 215 220 225 230 235 240 245 250 255 260 265 hinge is in open position and the other slot having walls for reenforcing the link connection when the hinge is closed.

4. A hinge structure comprising a base plate having a transverse member provided with oppositely disposed faces, a pair of links pivoted coaxially one to each face of said member, a block member pivotally secured at one end between said links, a second pair of links pivoted to the base plate and to said block and a movable plate provided with ears overlying portions of said block

and being pivoted thereto, said base plate having oppositely recessed side walls, one recess being adapted to receive said second pair of links and block when the hinge is in open position to reinforce the same, the forward ends of said first pair of links being arranged to fit snugly in said other recess when the hinge is in closed position.

In testimony whereof, I have subscribed my name.

LEON A. WOODRUFF.
